PHONOGRAPH

Pierre Joseph Bussoz, Paris, France

Application June 22, 1932, Serial No. 618,778
In France August 31, 1931

5 Claims. (Cl. 274—10)

The present invention relates to an improved phonograph of the type comprising, in combination, a reproducing device provided with a circular plate for rotating the record, a magazine containing the record, and an automatic device by which any selected record may be transferred from said magazine to the said circular plate, and inversely.

The said apparatus is chiefly characterized in that the device employed to transfer the record from the magazine to the circular plate and inversely, consists of a fork or analogous device provided with members for seizing the record, the movements of said fork or analogous device being such that said members for seizing the record are movable upon a given constant path between two stationary points, one of them being located above the said circular plate and the other being situated at a point in space before which the selected record is brought by a suitable displacement of said magazine.

According to another feature of the invention, the fork or other seizing device is pivotally mounted on a frame which is adapted to turn about a stationary axle pin and is connected, by a crank and a link, to a suitable fixed point, whilst a cam secured to the said frame actuates the said fork or like device.

According to a further characteristic of the invention, the selecting device which controls the displacements of the magazine is connected with a suitable device which assures, due to its position, the placing of the record upon the circular plate upon one side or the other of the record.

In a form of construction, one of the devices for seizing the record is secured to a shaft which is mounted on the said fork or like transferring device and is provided with a pinion co-operating with a rack, or a curved toothed member, which can be placed in or out of gear engagement by means of the selecting device.

Further characteristics of the invention will be set forth in the following description.

In the accompanying drawings, which are given solely by way of example:

Fig. 1 is a diagrammatic elevational view of an apparatus constructed in conformity to the invention, said apparatus being represented in the position corresponding to the moment when the record leaves the magazine.

Fig. 2 is an analogous view, showing the record at an intermediate point on its path, and

Fig. 3 a similar view in the position in which the record is adjacent the circular plate.

Fig. 4 is a like view, the record being placed upon the said plate.

Fig. 5 is a plan view of the device controlling the record carrying fork.

Fig. 6 is a partial elevational view showing the device adapted for releasing the record which is placed upon the circular plate.

Fig. 7 shows a modified form of the magazine.

Fig. 8 shows a general view of a phonograph with the details of the electric circuit.

Fig. 9 is a partial section on line 9—9 of Fig. 1.

In the form of construction represented in Figures 1 to 6, the apparatus comprises a stationary frame consisting of uprights 1 and horizontal cross-pieces 2. Upon the table formed by the said cross-pieces is mounted a reproducing device 3 of the acoustic or the electric type, whose stylus 4 moves over a record carried by a rotating plate 5, which may be actuated by any suitable mechanism.

Beneath the cross-pieces 2 is mounted a magazine 6 containing the records. In the present construction, the said magazine consists of a semi-cylindrical support in which are formed equidistant grooves 7, each of them being adapted to receive a record 8. All of the records have the vertical and parallel position, and are disposed side by side. The support 6 is movable in the direction of the arrow f^1 or in the contrary direction, and is carried and guided by rods 9 which are secured to the frame.

The magazine 6 can be displaced in any suitable manner, and for instance by means of a selecting device 10, of a known type, and provided with a sprocket wheel 11 adapted to drive a shaft 14 by means of a chain 12 and a sprocket-wheel 13. Said shaft carries a pinion 15 in gear engagement with a rack 16 secured to the support 6.

Upon the shaft 17 of the driving wheel 11 is mounted a cam 18. A lever 20 pivotally mounted upon a pin 21 bears upon said cam 20 through the intermediary of an arm 19. The outer end of the lever 20 carries a portion of a crown-wheel 22, whose position in height will thus depend upon the position of the cam 18 at its point of contact with the arm 19. The said cam 18 and the sprocket-wheel 15 actuating the rack 16 are so constructed that one unit rotation of the wheel 11 of the selecting device 10 assures alternately on the one hand a unit displacement of the rack 16 and hence of the magazine 6, and on the other hand the descent of the toothed member 22.

The apparatus further comprises a mechanism for the transfer of each record 8 from the magazine 6 to the phonograph plate 5, and in-

65

versely. A frame 24 is pivotally mounted upon a horizontal axle pin 23 secured to the uprights 1, said frame carrying two parallel and lateral plates 25. Upon the said frame is mounted an electric motor 26 (Fig. 5) adapted to drive—by means of the worm gearing 27—28—a shaft 29 journalled in lugs 30 and 31 pertaining to the frame 24. The shaft 29 drives—by worm gearing 32—33 or the like—a shaft 34 journalled for example in one of the plates 25; said shaft carries a disc 35 on which is pivotally mounted, in the eccentric position at 36, a link 37 which is pivoted at the other end to a stationary shaft 38 secured to the uprights 1. Thus when the motor 15 is in operation, and under the action of the crank-disc 35 and the link 37, the frame 24 will oscillate between two extreme positions, as shown in Figures 1 and 4 and Figure 2.

Upon the shaft 34 is keyed a pinion 39 (Figures 1 and 5) engaging a gear-wheel 40 which is keyed to a shaft 41 mounted in the plates 25 and carrying a cam 42 which is in contact with a roller 43 situated at the rear end of a fork 44.

The said fork 44 is pivotally mounted on a spindle 45 secured to said plates 25, and the distance between the two parallel branches of the fork somewhat exceeds the diameter of the records 8. At the end of each branch of the fork is mounted a device for seizing one of the records 8, said device may consist (Fig. 6) of a forked bracket 46 mounted at the end of a shaft 47 which is slidable in the end of the arm 44. A spring 48 urges the forked bracket in the direction of the arrow f^2 , for the engagement of said bracket with the record 8. The releasing of the bracket from the record 8 may be assured by any suitable means, for instance by mechanical or electric means. In the device shown in Fig. 6, the shaft 47 ends in knob 49 co-operating with a stationary ramp 50 (Figs. 1 and 6); said ramp may be mounted on the cross-piece 1 in the case where the record 8 is to be placed upon the plate 5 (Fig. 6), or on any suitable fixed support in case the disc is to be placed in the magazine 6.

Upon one of the shafts 47 is keyed a pinion 51 (Figs. 1 and 4), the device being so arranged that when the said shaft 47 is displaced on the path $abcd$, the pinion 51 will engage the curved toothed member 22 when the latter is in the lower position (the arm 19 being between two projections of the cam 18, as shown in Figs. 1 and 2). Due to this gear engagement, the pinion 51 and the shaft 47 will make half-a-revolution.

The mechanism is completed by devices 52 for guiding the record 8 when it begins to rise, and by stops 53 with which the record makes contact somewhat before the end of its movement towards the plate 5.

The operation is as follows. Under the combined action of the oscillations of the frame 24 and of the cam 42, the fork 44 oscillates between two extreme positions (Figs. 1 and 4), for which the shafts 47 of said fork will be brought into two fixed positions on the respective sides of the magazine 6 and above the plate 5. When the fork 44 is in the starting position, as shown in Fig. 1, the shafts 47 are placed out of action by one of the suitable devices above-mentioned, such as the stops 50; but when the fork begins to move in the direction of the arrow f^3 (Fig. 1) the forked brackets 46 are now released, and under the action of the springs 48 they seize the record which is now before them. Obviously, the herein seized record will depend upon the position of magazine 6, which position

is regulated by the selecting device 10. It will be supposed that the record to be employed is the first record on the left (Fig. 1). For this position of the magazine 6, the curved toothed member 22 is in the raised position. The first record 8a is thus raised out of the magazine. The form of cam 42 and the movement of frame 24 are such that the first part ab of the path of shafts 47 is vertical, and thus record 8a rises vertically, it being guided by the device 52. This vertical rise is necessary, in order that the record may be released from the magazine, this being particularly important in the case of the intermediate records.

The path then becomes curved from b to c , due to the form of cam 42 and the record 8a, which is now released from the guide 52, assumes an inclined position (Fig. 3). The record finally arrives at 8d, upon the plate 5, as shown in Fig. 4. At the end of the stroke of the fork 44, the knobs 49 situated at the ends of the shafts 47 make contact with the stops 50 and recede, thus releasing the record.

The operation for the return of the record to the magazine 6 is effected in an analogous manner.

As the records carry the record on both sides, it is necessary that they shall be laid upon the plate 5 on either side at will, and this result can be obtained by means of the selecting device 10 and the curved toothed member 22. In fact, in the case of the first record 8a and for the extreme position of the selecting device 10, for instance, this record 8a is laid upon the plate 5 with its left-hand side downwards (Fig. 1). If the selecting device 10 is moved by one unit, the cam 18 will now offer a recessed part to the arm 19 (as herein represented), and the pinion 15 will be out of engagement with the rack 16 of the magazine 6 (for instance by 115 separating the teeth of pinion 15 by a space twice as large as that of the teeth of rack 16), and hence the said magazine will remain in the fixed position, while the toothed member 22 descends. In this position, the same record 8a, which is the first to the left, for instance, will be again seized, but when in coincidence with the toothed member 22, the pinion 51 is now rotated and makes half-a-revolution, thus turning the record 8a to a like degree, and hence 125 the record will be laid upon the plate 5 with its right-hand side down (Fig. 1). On the return movement, the pinion 51 will turn the record in the other direction, and thus the record will be placed in the magazine 6 in the same position 130 as at the start.

When the selecting device 10 is operated by another unit, this will remove the toothed member 22 by raising it, and will also move forward the magazine 6 by one unit in the direction of the arrow f^2 (or in the contrary direction), and so on, by an alternate motion, in the case of an operation by separate units. Obviously, the magazine 6 may be displaced, in a single movement, by any suitable number of records without actuating the fork 44.

The above described mechanism may be operated by any suitable and known means. The following description will show together with Fig. 8 an example of such actuating means. It is first to be noted that the meshing gear wheels 40 and 39 are so arranged that the shaft 41 rotates at half the speed of shaft 34. On said shaft 41 is mounted a disc 55 provided with a notch 56. A lever 57 is pivotally mounted at 58 and is provided

with a point 59 and a finger 60. Said point is adapted to engage said notch 56, whereas the finger 60 is adapted to actuate a piece 61 against a reaction spring (not shown). The piece 61 in 5 turn actuates a contact 62. Electric current is supplied by the wire 63 up to a contact 64 on the selecting device 10. This contact may be operated by a coin and is of any known type. From contact 63 the wire leads to the motor 65 adapted

10 to drive the turntable 5. The wire enters the motor at 66 and leaves it at 67, it then passes over a contact 68 on the motor 26 for operating the oscillating frame and returns to the source.

Contact 66 is connected by a wire 69 on one hand with contact 62 and, on the other hand, with a contact 70, the latter being operated by the sound arm 3. Finally, the second point of contact 70' is connected by a wire 71 with contact 62 and contact 68.

20 The operation is as follows: A coin being introduced into a suitable chute on the selector 10, contact 64 is closed and current is supplied to motor 65 which begins to rotate. Contact 62 being normally closed, the motor 26 also rotates and the forked member 44 raises the record. The rotation of motor 26 continues until point 59 engagess notch 56, lever 57 being then rotated and opening, by means of finger 60 and piece 61, contact 62. The motor 26 stops and at this moment 30 the record is already situated upon turntable 5.

The member 44 at the end of its motion and while lowering the record has actuated by means of finger 72 a piece 73 which in turn provokes the rotation and lowering upon the record of arm 3 due to suitable ramps (not shown). When the record has been played, the arm 3 occupies a position adjacent contact 70 and closes this latter. Thus current is again supplied to motor 26 which latter begins to rotate, disengages point 59 thus 40 closing contact 62. Arm 3 is raised and brought aside and record 8a brought back into the magazine. When at the end of its track arm 44 actuates, any spring operated lever and opens contact 64. In this way roller 43 is displaced upon half 45 the periphery of cam 42 when the record is raised out of the magazine and upon the second portion of this cam when bringing the record back into the magazine.

It is obvious that the said magazine need not 50 necessarily be moved in a rectilinear direction, but it may be given for instance, a rotary motion, and in this event the records will have the radial position, as shown in Fig. 7, and the motion by means of the selecting device may be obtained 55 in any suitable manner.

The said invention is not limited to the forms of construction herein described and represented, which are given solely by way of example, and for instance, the device 46 for seizing the records may have any suitable form, such as a fork, a 80 clamp, or the like.

Having now described my invention, what I claim as new and desire to secure by Letters Patent is:

1. In a record changing mechanism according to claim 3, the further feature residing in that said clamping means are adapted to yieldingly engage the selected record, and fixed stops are adapted to cooperate with said seizing means for releasing said record when in position upon said rotary plate and in the magazine. 85

2. In a magazine phonograph, a record changing mechanism comprising means for conveying a selected record from the magazine onto the rotary record supporting plate, selecting means controlling the displacements of the magazine, a relatively fixed toothed member operatively connected with said selecting device, a shaft provided on the conveying means and supporting the record carrying members, and a pinion mounted 90 on said shaft and adapted to temporarily cooperate at will with said toothed member on its path from the magazine toward said rotary plate and inversely for overturning said record. 95

3. A record changing mechanism comprising 100 clamping means for positively seizing a record in the magazine, conveying means pivotally supporting said clamping means and adapted to positively raise a selected record out of said magazine to convey and to lay it on the rotary plate of the 105 phonograph and to bring it back into the magazine after it has been played and to follow thereby a continuous path, a cam actuating said conveying means, a motor controlling said cam, an oscillating frame pivotally supporting said cam and 110 said conveying means, and means for oscillating said frame. 115

4. In a record changing mechanism according to claim 3, the further feature residing in that record-guides are provided over the record magazine for avoiding the rotation of said clamping means and thus for maintaining the raised record in a vertical plane until the record has completely left the magazine. 120

5. A record changing mechanism according to 125 claim 3, wherein said frame oscillating means consist of a crank and link device operatively connecting said motor and said frame.

PIERRE JOSEPH BUSSOZ. 130
